United States Patent

Des. 237,623
Patented Nov. 11, 1975

237,623

MAGAZINE FOR STORING INFORMATION ON TAPES

Paul A. Morgan, Chicago, Ill., assignor to Century
Wheels Research Corp., Lake Bluff, Ill.

Filed Aug. 8, 1973, Ser. No. 386,629

Term of patent 14 years

Int. Cl. D14—99

U.S. Cl. D26—14 B

FIG. 1

FIG. 2

FIG. 4

FIG. 5

FIG. 3

FIG. 7

FIG. 1 is a perspective view of a magazine showing my new design;

FIG. 2 is a top plan view of the magazine shown in FIG. 1;

FIG. 3 is a bottom view of the magazine shown in FIG. 1;

FIG. 4 is a rear elevational view of the magazine shown in FIG. 1;

FIG. 5 is a side elevational view showing the right side of the magazine of FIG. 1;

FIG. 6 is a front elevational view of said magazine; and

FIG. 7 is a side elevational view showing the left side of the magazine of FIG. 1.

I claim:

The ornamental design for a magazine for storing information on tapes, as shown and described.
